TIP FOR CUTTING TORCHES

Filed Aug. 23, 1926

UNITED STATES PATENT OFFICE

GEORGE C. QUELCH, OF OAKMONT, PENNSYLVANIA, ASSIGNOR TO INTERNATIONAL OXYGEN COMPANY, OF NEWARK, N. J., A CORPORATION OF NEW JERSEY

TIP FOR CUTTING TORCHES

Application filed August 23, 1926. Serial No. 130,888.

My invention refers to an improvement in the class of cutting tips for torches for the cutting of ferrous metals.

In such torches, which are now in large and common use, a preheating flame of high temperature is first directed against the metal to be cut, and, when the combustible temperature of the metal is reached, a jet of pure oxygen under pressure is directed against the heated portion, (with a corresponding cessation of the preheating flame).

Combustion of the metal, under the oxygen jet, then occurs, reducing the metal to magnetic oxide of iron, the pressure jet of oxygen forcing the oxide through and away from the narrow surf made in the metal as the cutting action proceeds along a given line.

In torches of this general class, the device is usually provided with three supply pipes or conduits, leading to the terminal head embodying the tip, providing for the supply of high pressure oxygen for cutting, low pressure oxygen, and a combustible gas for burning therewith for preheating.

In general practice, there are two main classes or types of tips utilized; first, where the combustible mixture of oxygen and fuel gas, for preheating, is formed or combined within the torch proper or within its head; second, where the combustible mixture is formed between balanced gases or by proper relation of the conducting orifices, or by injector action within the torch tip itself, mounted in the surrounding head.

There are also variations in the terminal construction of the tip, which may be either plane across the delivery end with all of the jet openings emerging on the same plane, or with the tip of the jet recessed, providing a forwardly extending tubular shell for protection of the preheating flame.

The plane end tips are ordinarily used for fuel gases having a kindling or igniting point below 600° C., such as hydrogen, igniting with an igniting point of 580° C., or acetylene at 480° C.

The recessed tips are ordinarily used for fuel gases having a kindling or igniting point above 600° C., as in the case of hydrocarbon

gases, which liquefy within a container at or below the pressures usually considered standard for low or high pressure containers.

In the use of such gases for metal cutting with torches of the class involved, it has been necessary, and the practice is common in the industry, to use a tip designated as a recessed tip. 55

The object of my present invention is to provide a cutting torch tip for the purpose of securing a more stable preheating flame with a gaseous mixture of high kindling or igniting point, as above 600° C. 60

This object is secured in the constructions shown, by providing the individual preheating gas delivery holes, adapted to conduct the gaseous mixture under uniform pressure to a point considerably in the rear of the delivery end of the jet, with an appreciable enlargement thereof which is thereafter extended to a point immediately in the rear of the end of the tip, and with a final further enlarged delivery opening for each hole. In the constructions shown, this feature of the invention is embodied in both of the main classes of tips above identified, and as herein-after more fully described. 65

In the accompanying drawings, showing certain preferred embodiments of the inventions, — 70

Fig. 1 is a sectional view of the head of a cutting torch provided with my improved tip; 75

Fig. 2 is an enlarged longitudinal sectional view of such tip, providing for admixture of the combustion gas and oxygen within the tip itself; 80

Figs. 3, 4 and 5 are cross sections on the lines III, III, IV, IV, and V, V, respectively, of Fig. 2; 85

Fig. 6 is a view of the delivery end of Fig. 2; 90

Fig. 7 is a sectional view of another construction of tip, of the second class, partly in elevation; 95

Fig. 8 is a cross section on the line VIII, VIII, of Fig. 7.

Referring to the drawings, A is the head of a standard torch, having the usual high pressure oxygen pipe 2, a low pressure oxygen pipe 100

pipe 3, and a gas supply pipe 4 communicating with the several corresponding passages 5, 6 and 7. As is generally understood in the art, the preheating mixture is effected by mixing the low pressure oxygen from port 6 with the preheating gas, as acetylene, hydrocarbon, etc., in passage 7. The jet member *a* is of well known construction as to its upper portion, having the central high pressure oxygen passage 8 communicating with passage 5 and the surrounding plural passages 9 for the gaseous mixture, located equidistantly around the central oxygen hole and terminating at the end of the jet. In my construction the inner or receiving end holes 9 are branched as at 10 and 11, for communication with the low pressure oxygen passage 6 and the gas passage 7 respectively.

By reason of such arrangement, there is an injector action effected, the oxygen and gas entering holes 9 together and becoming mixed in their passage toward the delivery end.

At a point considerably in rear of the delivery end of the jet *a*, passages 9 are materially enlarged as at 12, backwardly of the end of the tip for say approximately three-quarters of an inch, more or less. The delivery terminals of the several passages 12 are also further enlarged by the flaring or bell-shaped delivery terminals 13, all delivering outwardly through the end of the tip on the same plane as the high pressure oxygen hole 8.

In the construction shown in Figs. 7 and 8, the tip *b* is constructed to secure the same results in effect by the utilization of gas mixture grooves 9^a of uniform size, adapted to receive the oxygen and gas mixture as delivered within a suitably constructed head, like head B, for introduction of the mixture to the grooves.

Tip *b*, within and beyond the head, is provided with an outer surrounding shell or enclosing tube 14 which confines the gaseous mixture until it reaches a common annular chamber 15, beyond which, for a short distance, are the reduced conduction grooves 9^b. Said grooves 9^b correspond generally to the passages 9 of the one-piece jet *a*, and communicate with the enlarged grooves 12^b, and the final further enlarged or flaring emission grooves 13^b.

The shell 14 fits tightly around the circular exterior of the tip, as in Fig. 8, and is provided with corresponding grooves 16, maintained in register with grooves 12^b by any suitable means, and terminal enlarged delivery openings forming the outer portions of the openings 13^b.

Tip *b* is also provided with the usual central high pressure oxygen passage 8^b communicating at the other end with high pressure oxygen channel 5 of the head.

The purpose of the first enlargement 12 or 12^b of either construction is to reduce the

velocity of the gaseous mixture flowing through the preheating holes, with a corresponding reduction of pressure. The second or terminal enlargement 13 or 13^b shortens up the flame cones, and gives the flame more stability.

In other words, there is as a result, ample supply of gaseous mixture with no tendency for the flame to blow away from the end of the tip when a given quantity of gases are passing through the preheating holes, as would be the case if the passages 9 were continued uniform through to the end, as is the common practice. I am, therefore, able to deliver the preheating gases through the end of the tip on the same plane as the emission jet of the high pressure cutting oxygen, without the necessity of any shrouding or protecting tubular extension beyond the passage terminals. As a result there is no tendency for the preheating flame to be disturbed when the cutting jet of oxygen is operating, as is the case when such recessed tip is used.

My experiments with hydrocarbon gases, having high kindling or igniting temperatures, have shown that with a cutting equipment designed for gases of low kindling point, a flame cannot be held at the end of a plane tip, unless the flame were highly oxidized. Such over-oxidation is objectionable because it materially reduces the flame temperature.

When a hydrocarbon gas is mixed with a proper proportion of oxygen, to secure maximum flame temperature, the flame will not burn continuously at the end of the tip, unless the volume is decreased to a fraction of the volume for which a given size tip was designed. Such decrease of volume is effected by lowering of pressure, so that a hydrocarbon gas of high ignition point will burn at the end of the tip if the pressure or velocity of the mixture at the point where the gases leave the tip, is thus lowered.

It is well understood that it is necessary to burn a comparatively large volume of combustible gas mixture in a small area in order to raise the temperature of the metal locally to the combustion point in the shortest possible time. The lowering of pressure at the end of the tip when effected only by a lowering in volume necessarily decreases the capacity of a given size tip, with a consequent increase in preheating time.

In my invention I secure the desired lowering in pressure, without any decrease in volume of the hydrocarbon fuel gas mixed with the proper proportion of oxygen, and secure the maximum flame temperature obtainable. This result is directly due to the enlargement of the individual jet passages themselves for a material distance backwardly of their emission terminals, in either of the constructions shown, and as above described.

It will be understood, of course, that the

number and arrangement of the surrounding mixture passages may be changed or varied within the judgment of the designer or skilled mechanic, and with regard to the kind of work to be performed and the gaseous mixture employed. I, therefore, do not desire to be limited to the particular construction shown, but to include such variations within the scope of the following claims.

10 What I claim is:

1. In a cutting tip for torches, the combination with a supply head, of a compound cutting tip consisting of an inner tip member having a central oxygen duct and outer longitudinal grooves, and a surrounding shell having longitudinal grooves registering therewith and enlarged at their outer portions.
- 15 2. In a cutting tip for torches, the combination with a supply head, of a compound cutting tip consisting of an inner tip member having a central oxygen duct and outer longitudinal grooves, and a surrounding shell having longitudinal grooves registering therewith and provided with an intermediate and a final terminal enlargement.
- 20 3. In a cutting tip for torches, the combination with a supply head, of a compound cutting tip consisting of an inner tip member having a central oxygen duct, an annularly reduced common mixing portion and longitudinal delivery grooves, and a surrounding shell having longitudinal grooves registering therewith and enlarged at their outer portions.
- 25 4. In a cutting tip for torches, the combination with a supply head, of a compound cutting tip consisting of an inner tip member having a central oxygen duct, an annularly reduced common mixing portion and longitudinal delivery grooves, and a surrounding shell having longitudinal grooves registering therewith and provided with an intermediate and a final terminal enlargement.

35 In testimony whereof I hereunto affix my
40 signature.

GEORGE C. QUELCH.
